TAKE-UP MECHANISM FOR KNITTING MACHINES

Arthur Theobalt, Laurelton, N. Y.

Application July 21, 1945, Serial No. 606,307

1 Claim. (Cl. 66—149)

This invention relates to improvements in take up mechanisms for knitting machines. The object of the invention is to provide improved supporting means for the friction driven roller of such mechanism. The specific objects of the invention, its novel features and the advantages of the improvements disclosed herein will be best understood from the following specification read in connection with the accompanying drawing in which

Fig. 1 is a side view of a take up mechanism embodying the invention.

Fig. 2 is a plan view with parts broken away.

Fig. 3 is a sectional view of one end of the friction driven roller.

Fig. 4 is a view illustrating the novel features and the advantages of the invention.

The operation and purpose of a take up mechanism in a knitting machine is known in the art. As the knitted fabric comes from the knitting needles it is passed through the take up mechanism which exerts a steady pull on the finished fabric and conveys it out of the machine. It is therefore important that there be no obstructing elements in the take up which may cause uneven operation or backing up or bunching of the fabric thereby injuring the same. The invention disclosed herein prevents any binding or undesirable friction in the running of the take up roller and eliminates damage which frequently occurs due to the manner in which the friction driven roller is supported in prior devices.

Referring to Figure 1 the numeral 5 indicates the power driven take up roller. This is a knurled roller which may be driven by a well known form of gear and pawl device as indicated at 6. The knitted fabric 7 comes down from the knitting needles, not shown, passes around the roller 5 and then over the take up roller 8 which is another knurled roller driven frictionally from the roller 5. The two rollers pull the fabric between them and convey it out from the machine as is well known.

The take up roller 8 is supported in two arms 9, 9 which are pivoted on and rest upon a transverse bar 10 which is a regular part of the knitting machine. The roller 8 is held against the roller 5 by a counterweight 11 which is hung on a transverse shaft 12 supported in the ends of the arms 9 as shown. All parts of a knitting machine vibrate during the operation and in order to avoid binding or friction between the arms 9 and the roller shaft, the arms are individually hung on the bar 10 and loosely supported thereon.

The shaft 12 is also loosely supported in the arms 9.

Heretofore it has been the practice to support the roller 8 in the arms 9 by means of studs extending from the ends of the roller or by having the central shaft to which the roller is secured and with which it rotates extend beyond the ends of the roller and through bearings or apertures in the ends of the arms 9. When therefore the arms 9, because of the vibration accompanying the operation of the machine, moved unevenly, the bearing ends of the arms which supported the roller shaft would become out of alignment and perhaps angularly inclined towards each other. In such positions of the arms, the roller shaft would be caught in its bearing supports and no longer be able to run true and free in cooperation with the power driven roller.

In accordance with this invention the friction roller 8 is mounted to rotate upon the roller shaft and not in the supporting arms 9. Hence any binding or friction between the ends of the shaft and its support in the arms 9 is not transferred to the roller which continues to rotate evenly in contact with the roller 5. Hence any backing up or bunching of the fabric is avoided and damage eliminated.

With this object in view the knurled roller 8 is constructed as shown in Figure 3 and preferably comprises a metal inner tube 14 with an outer friction cover tube 15. The roller shaft 16 is supported directly in the arms 9 and is prevented from rotating therein by being flattened, for example, as shown at 17 so as to rest in the bearings 18 in the arms shaft in non-rotatable relation.

The take up roller 8 rotates freely upon the shaft 16 through ball bearings 20, 20 in a well known manner. During the operation of the knitting machine the arms 9 are free to tip individually upon the bar 10 and also have free lateral movements. This is necessary in order to avoid stiffness in the take up mechanism. However, binding and undesirable friction occurs anyway because with prior devices the ends of the roller shaft would all too frequently be caught in its supporting bearings in the ends of the arms 9. With the improvement disclosed herein the friction roller will run free on the shaft 16 even through the latter should become tilted and caught, frictionally, in the arms 9.

The take up roller 8 rotates at all times freely upon its shaft 16 in response to the friction from the roller 5 and its rotation is not disadvan-

geously affected by any friction or binding movement between the shaft 16 and the arms 9. The disclosed device is in actual operation in knitting machines and satisfactorily accomplishes the objects of the invention.

I claim:

In a take up mechanism for knitting machines, a power driven roller, a second tubular take up roller rotated by frictional engagement with the power driven roller, said rollers being adapted to take up the knitted fabric from the knitting machine, means for supporting said tubular second take up roller comprising a fixed bar, a pair of

arms pivoted on said bar intermediate the ends of the arms, a shaft supported in the ends of said arms, means preventing rotation of said shaft in said arms, ball bearings on said shaft for supporting the said tubular second take up roller on the shaft in freely rotating relation thereon, said tubular take up roller encasing the said shaft and a counterweight supported in the opposite ends of the said arms for maintaining said tubular second take up roller in constant driving engagement with the said power driven roller to be rotated thereby.

ARTHUR THEOBALT.
